UNITED STATES PATENT OFFICE

2,450,575

MEANS FOR WORKING RUBBER

Stewart Bolling, Cleveland, Ohio

Application July 13, 1945, Serial No. 604,746

2 Claims. (Cl. 18—2)

This invention relates to a means for working rubber, and more especially to machines of the type known as mixers, extruders, etc. In machines for mixing synthetic or natural rubber, plastics, mastics and like substances, it has been found necessary to heat or chill the chamber wherein the material is being worked and it is an object of the present invention to provide new and improved means whereby either a heating agent or a chilling agent can be utilized for controlling the temperature of the material under treatment.

As is well known to those skilled in the art, it is necessary, under some conditions, to heat the batch of material during the beginning of the mixing or kneading operation and thereafter to chill the material so as to prevent setting, or partial vulcanization or thermo setting before the ingredients are thoroughly dispersed.

The present invention has for its object the provision of a new and efficient means whereby the heating or chilling medium can be properly applied for the purpose of obtaining the results desired, this medium flowing in a continuous stream back and forth from top to bottom within the side wall of the mixer.

It is a further object to provide a novel form of side wall for mixers of this type the interior portions of which are readily accessible for cleaning purposes and are so constructed as to permit easy construction with a novel arrangement of ribs whereby a tortuous flow of the medium is made possible and it becomes unnecessary to use sprays or the like as heretofore required in order to get the best results.

With the foregoing and other objects in view which will appear as the description proceeds, the invention consists of certain details of construction and combinations of parts hereinafter more fully described and pointed out in the claims, it being understood that changes may be made in the construction and arrangement of parts without departing from the spirit of the invention as claimed.

In the accompanying drawings, the preferred form of the invention has been shown.

In said drawings,

Figure 1 is a central vertical section through a mixer having the present improvements combined therewith.

Figure 2 is a section on line 2—2, Figure 1.

Figure 3 is an outer elevation of the wall of one of the cylinders of a mixing machine.

Figure 4 is an elevation of the inner side of the

cover or baffle plate which cooperates with said wall.

Referring to the figures by characters of reference, 1 and 2 designate opposed communicating cylinders forming the mixing chamber in a mixer of a well known type, there being a rotor 3 supported for movement within each of the cylinders adjacent to a center door or gate 4 which is normally closed.

10 It has usually been the practice to chill the arcuate walls 5 of the cylinders by the use of spraying equipment. The means employed have not been adaptable to the use of a heating medium and, as heating is frequently required in addition 15 to cooling in the treatment of new materials, such as synthetic rubber and plastics, no satisfactory structure has been devised whereby both the heat and cold can be utilized in any desired succession and for any desired periods of time. Furthermore, 20 the chilling means heretofore employed and utilizing sprays have disadvantages due to the fact that it has been difficult to prevent corrosion, scaling or flaking resulting from the medium used for chilling purposes, nor has it been an easy 25 matter to obtain access to the parts for the purpose of cleaning them.

In the present instance, the desired results are obtained by providing on each of the walls 5 a box-like extension 6 formed of upper and lower 30 walls 7 and side walls 8 adapted to be engaged by a cover plate 9 which can be held in place by bolts 10 or the like and which can be fitted snugly between the side walls 8 so as to bear upon flanges 11 forming seats.

35 The space within the box-like extension 6 has spaced parallel longitudinal ribs 12, 13 and 14 cooperating with the upper and lower walls 7 and with each other to provide parallel channels 15, 16, 17 and 18.

40 Arranged on the outer surface of wall 5 are arcuate fins 19 extending from the top to the bottom of each channel. Any desired number of these fins can be applied, but it is desirable to have them widely spaced, as shown in Figure 3.

45 A port 20 is provided in one end portion of the wall 7 and another port 21 is provided in one end portion of the other wall 7. One of these ports constitutes an inlet for the temperature controlling medium, while the other port constitutes an outlet, there being any suitable arrangement of pipes 22 leading to and from the ports.

50 A passage 23 is provided in that end of rib 12 remote from the adjacent port 20. Another passage 24 is provided in rib 13 at that end thereof

remote from passage 23. Another passage 25 is provided in rib 14 at a point substantially in line with passage 23 and remote from the port 21.

As shown particularly in Figure 1, the ribs 12, 13 and 14 are of different sizes due to the fact that they extend from an arcuate wall 5 and that their outer ends are flush with the walls 7 and the flanges or seats 11. All of these ribs, as well as the walls 7 provide seats for the cover plate 9 which has an arcuate inner surface 26 concentric with but spaced from the outer surface of the wall 5. Slots 27 are provided in the cover plate and are proportioned and located so that the several ribs, 12, 13 and 14 will fit snugly therein. These slots divide the inner portion of the cover plate into filling blocks 28, 29, 30 and 31 and formed on the inner faces of these filling blocks are fins 32 which project between the fins 19 as shown particularly in Figure 2 and extend transversely of the channels 15, 16, 17 and 18.

It will be apparent from the foregoing explanation that a temperature controlling medium used either for chilling or heating purposes can be directed through one of the ports 20 or 21 into one end of one of the channels. Assuming that the medium enters at port 20, it can reach the port 21 solely by following a tortuous path leading along the channel 15 from port 20 to passage 23, thence along channel 16 to passage 24, thence along channel 17 to passage 25 and finally along channel 18 to port 21. The successive courses of the tortuous path are located in an arc concentric with the inner arcuate surface of the wall carrying them. During this movement along a tortuous path the medium must flow past the alternately arranged fins 19 and 32 with the result that the medium is agitated and caused to form eddies or open areas which, during a cooling operation, cause vapor tension resulting in better cooling. The alternately arranged baffles or fins are useful for the transfer of thermal units during a heating operation.

Obviously, the apparatus can quickly be changed from a heating to a cooling machine and vice versa simply by changing the type of temperature controlling medium admitted thereto. As there are no nozzles or other devices likely to become clogged and rendered inefficient, the efficiency of the present structure can be easily maintained. However, should the passage ways become partially choked from any cause, it is possible readily to clear them simply by removing the cover plates and the filling blocks integral therewith so that all surfaces of the passages are thus exposed where they can be easily cleaned.

In a machine such as described it is easy to meet those conditions in the mixing of synthetic rubber and plastics requiring the heating of the material being worked, during the first portion of the mixing operation followed by a chilling action so as to prevent setting or partial vulcanization or thermo setting before the ingredients are thoroughly dispersed.

It is to be understood, of course, that both sides of the machine are of duplicate construction so that the temperature controlling mediums can thus be circulated over the outer surfaces of the walls of both cylinders 5.

As the two cylinders cooperate to form a working chamber having the outlet gate or door 4, it will be obvious that interchange of thermal units through the walls 5 of the working chamber and cylinders will result in rapid change of temperature of the material under treatment.

What is claimed is:

1. A machine of the class described including a working cylinder having an arcuate wall, a box like extension on and extending outwardly from said wall, the extension including parallel upper and lower walls and parallel side walls, said upper and lower walls and side walls having flush outer edges, spaced longitudinal ribs, defining longitudinal channels, on the cylinder wall disposed parallel to, and having their outer edges flush with the outer edges of, the upper and lower walls of the extension, there being a passage at one end of each rib providing communication between adjacent channels, each passage being oppositely disposed relative to the next adjacent passage, spaced arcuate fins on the cylinder wall extending transversely across each channel, a cover plate removably connected to the outer edges of the upper and lower walls and side walls of the extension, said plate having an arcuate inner surface spaced from, and concentric with, the cylinder wall, the plate having longitudinal slots wherein the longitudinal ribs are received, and transverse arcuate fins on the inner surface of the plate disposed alternately to the fins of the cylinder wall.

2. A machine of the class described including a working cylinder having an arcuate wall, an extension on and extending outwardly from said wall, said extension including parallel upper and lower walls and parallel side walls, spaced longitudinal ribs, defining longitudinal channels, on the cylinder wall disposed parallel to the upper and lower walls of the extension, there being a passage at one end of each rib providing communication between adjacent channels, each passage being oppositely disposed relative to the next adjacent passage, spaced transverse arcuate fins on the cylinder wall extending across each channel, a cover plate removably connected to the upper and lower walls and side walls of the extension, said plate having an arcuate inner surface spaced from, and concentric with, the cylinder wall, the plate having longitudinal slots wherein the longitudinal ribs are received, and transverse arcuate fins on the inner surface of the plate disposed alternately to the fins of the cylinder wall.
